HYDROCARBON OIL CONVERSION

Clarence W. Luton and John Beddow, Toledo,
Ohio, assignors to Universal Oil Products Com-
pany, Chicago, Ill., a corporation of South
Dakota

Application August 7, 1930, Serial No. 473,547

2 Claims. (Cl. 196—48)

This invention relates to the treatment of hydrocarbon oils, and refers more particularly to the conversion of higher boiling hydrocarbons into lower boiling hydrocarbons.

5 In its general aspect, the invention provides an improvement in a process for the treatment of hydrocarbon oils, comprising subjecting the hydrocarbon oils to heat treatment at a conversion temperature, discharging the heated hydrocarbons into an enlarged reaction zone, and thereafter separating the vaporized and unvaporized materials for further treatment.

In a specific embodiment, the invention provides an improvement in a process for the treatment of hydrocarbon oils, which comprises introducing at definite levels in the reaction chamber reflux condensate from the process, or a similar oil of lower boiling characteristics than the unvaporized residue withdrawn from the reaction chamber. Examples of such lower boiling oils are: pressure distillate bottoms, kerosene distillate, light gas oils, etc. The reflux condensate may be obtained from a primary or secondary fractionating device or both. Preferably, the reflux condensate or other lower boiling liquid is introduced at the interface or contact surface between the unvaporized residue and the vapors in the reaction chamber. This interface, or the point just below it, is termed the "black" level because material withdrawn by means of try cock levels below the interface is black and opaque, indicating unvaporized liquid residue, whereas that withdrawn above is more or less translucent, indicating that vapors have been withdrawn. As the level in the reaction chamber is changed, the point of introduction of the lighter oil is correspondingly changed.

Among the objects of the invention is to provide a process for lengthening the operating cycle, increasing the yield of gasoline, improving the quality of the residuum, and eliminating operating difficulties, such as stoppage of residuum draw-off lines, and increasing the over-all flexibility of operation.

This is accomplished by cutting down the reaction temperature within the liquid body in the manner hereinafter described, preventing the formation of coke and suspended carbonaceous matter or pitchy material, which causes clogging of the draw-off lines. This permits a higher conversion temperature in the heating element, increasing not only the gasoline per pass but the over-all yield.

55 Other desirable features of the invention will

be more fully illustrated by reference to the accompanying drawing, which is diagrammatic and not to scale, and which represents one form of apparatus suitable for carrying out the process of the invention.

Raw oil charging stock is passed through line 1, controlled by valve 2, and is pumped by means of pump 3 through line 4, controlled by valve 5, into the dephlegmator 6, where it is contacted and undergoes heat exchange with the ascending vapors, preheating the raw oil and causing a partial condensation of the heavier components of the vapors arising in the dephlegmator 6.

A portion or all of the raw oil may be passed through line 7, controlled by valve 8, and through line 9 into the heating element 10 located in furnace setting 11. The oil heated to its conversion temperature passes through the transfer line 12, controlled by valve 13, into the reaction chamber 14. The vapors leaving the reaction chamber 14 pass through line 15, controlled by valve 16, into the dephlegmator 6. The reflux condensate from the dephlegmator 6, together with the raw oil, passes through line 17, controlled by valve 18, and is pumped by means of pump 19 through line 20, controlled by valve 21, into the heating element 10. The vapors leaving the dephlegmator 6 pass through line 22, controlled by valve 23, into cooler and condenser 24. The liquid, together with gases, passes through line 25, controlled by valve 26, into the receiver 27. The liquid is withdrawn from receiver 27 through line 28, controlled by valve 29. The gases are withdrawn through line 30, controlled by valve 31. A portion of the liquid may be recirculated from the receiver 27 through valve 32 and line 33 by means of pump 34, through line 35, controlled by valve 36, into dephlegmator 6, where it assists in cooling the vapors therein and regulating the boiling range of the distillate leaving the dephlegmator 6.

Unvaporized liquid residue from the reaction chamber 14 may be withdrawn through one or several of the lines 37, 38, 39, 40, controlled by valves 37', 38', 39', 40', through manifold line 41, where it may be collected and sent to storage or used for other purposes.

As a feature of the invention, a portion of the reflux condensate passing through line 20, controlled by valve 21, may be diverted through line 51, valve 52 and cooler 53 and thence passed through line 42, controlled by valve 43, into one or several of lines 44, 45, 46, 47, controlled by valves 44', 45', 46', 47', the particular line and

valve selected depending upon the level within the reaction chamber. A suitable oil, preferably lighter than the residuum withdrawn from the reaction chamber, and more preferably of a distillate character, may be pumped by means of pump 48 through line 49, controlled by valve 49', and through line 50, controlled by valve 50' into line 42 and thence into reaction chamber 14 as already described.

10 As a specific example of the results obtained by the operation of the process of the invention, when the residuum is not cooled and recirculated in the manner described, a yield of approximately 44% gasoline is obtained, producing at the same 15 time a yield of approximately 44% residuum of an average A. P. I. gravity of 13, containing from 6% to 8% B. S. or suspended carbonaceous matter. The percentage of coke, gas and loss was approximately 5%. The amount of coke made was approximately 4 pounds per barrel of cracking stock.

20 The operating conditions during this run were

In this operation, the transfer temperature was increased to approximately 925° F., without any difficulty due to stoppage of the residuum draw-off lines. The pounds of coke per barrel of raw oil charged was reduced from approximately 4 pounds to approximately 2 pounds or less. The charging capacity per stream day was increased from approximately 2200 barrels to approximately 2400 barrels. The number of hours on stream was increased from approximately 200 to 10 approximately 300. The coke deposited in the upper tubes of the heating element was reduced considerably by the operation of our improved process.

The pressure on the reaction chamber in this 15 run was maintained at approximately 185 pounds per square inch, with equalized pressures on the other elements of the system.

The following specific data further illustrates the results obtained in the operation of the 20 process of our invention:

approximately 900° F. temperature, that is, the temperature of the oil leaving the heating element, 850° F. temperature of vapors to the dephlegmator, 475° F. temperature of vapors to the condenser, maintaining a pressure of 180 pounds per square inch throughout the system. The capacity in barrels of cracking stock per stream day in this operation was approximately 2200.

65 When recirculating approximately 5% pressure distillate bottoms based on the charging stock, or other similar distillates such as kerosene distillate, we have been able to increase the gasoline yield to approximately 48%, and while 70 the residuum percentage was decreased to approximately 39%, its B. S. content was reduced from approximately 8% to approximately 0.6%.

The charging stock utilized in both cases was a 24-25 A. P. I. gravity topped Mid-Continent crude.

The above examples will serve to illustrate the advantages of our invention, but inasmuch as they are illustrative they should not be construed as limitations upon the broad scope of our invention.

We claim as our invention:

1. A hydrocarbon oil cracking process which comprises passing the oil in a restricted stream through a heating zone and heating the same therein to cracking temperature under pressure, discharging the heated oil into a vapor separating zone above the liquid level therein and separating the same therein into vapors and unvaporized oil, maintaining the latter zone under cracking conditions of temperature and pressure, introducing into said separating zone adjacent the contact surface between vapors and unvaporized oil therein a relatively cool oil of lower boiling point than said unvaporized oil, said rel-

5 atively cool oil being introduced at a temperature and in amount such as will substantially reduce coke and sludge formation in the unvaporized oil, and during the operation of the process varying the point of introduction of said relatively cool oil to the separating zone in accordance with variations in the liquid level of unvaporized oil therein.

10 2. A hydrocarbon oil cracking process which comprises passing the oil in a restricted stream through a heating zone and heating the same therein to cracking temperature under pressure, discharging the heated oil into a vapor separating zone above the liquid level therein and separating 15 the same therein into vapors and unvaporized oil, passing the separated vapors to a dephlegmating

zone and condensing insufficiently cracked fractions therein as reflux condensate, passing a portion of the reflux condensate through a cooling zone and thence into said separating zone, introducing the thus cooled portion of the reflux condensate into the separating zone adjacent the contact surface between vapor and unvaporized oil therein in amount sufficient to substantially reduce coke and sludge formation in the unvaporized oil, passing another portion of the reflux 10 condensate from the dephlegmating zone directly to the heating zone without appreciable cooling thereof, and condensing the dephlegmated vapors as a product of the process.

CLARENCE W. LUTON. 15
JOHN BEDDOW.
